UNITED STATES PATENT OFFICE.

HAROLD G. WARR, OF PARK RIDGE, ILLINOIS, ASSIGNOR TO THE P & M COMPANY, OF CHICAGO, ILLINOIS, A CORPORATION OF ILLINOIS.

TOOL FOR APPLYING RAIL ANCHORS.

Application filed July 27, 1927. Serial No. 208,800.

My invention relates to a tool for applying rail anchors to railroad rails.

The primary object of the invention is to provide an improved tool suitable for use in applying to railroad rails spring yoke rail anchors of the type in which the yoke is torsioned and driven transversely of the rail to its applied position.

A more specific object is to provide an improved tool of the above character adapted to so engage one jaw end of a rail anchor and the adjacent edge of the rail base that movement of the tool transversely of the rail elevates the lower edge of the said adjacent jaw to a position above the upper longitudinal edge of the rail base flange and also subjects the anchor to the desired torsional stress to move the jaw end of the anchor into a position whereby the gripping surfaces of the adjacent jaw end of the anchor will bear substantially flat against the surfaces of the rail base so as to provide a firm frictional grip thereon. By the use of my invention, I minimize the spring pressure of the anchor jaw upon the rail base during the application of the anchor and thereby avoid any substantial swaging or crushing of the sharp forward edge of the anchor jaw as said edge rides upwardly on the inclined top surface of the rail base.

A further object of the invention is to provide a tool of the above character which is so constructed as to distribute the pressure of the tool upon the rail base and thereby avoid excessive wear of the cam surfaces of the tool and which, when the anchor assumes a predetermined position, will be relieved of the spring pressure of the yoke so that the applying tool may be easily removed from the rail.

The invention consists in the new and improved construction hereinafter described and claimed for carrying out the above stated objects and such other objects as will appear from the description of the two embodiments of the invention and set forth in the appended claims.

In the drawings:

Fig. 1 is a side view of a rail anchor and one embodiment of my improved applying tool.

Fig. 2 is an end view of the anchor and applying tool illustrating the same positions of said members shown in Fig. 1.

Fig. 3 is a fragmentary view similar to the left hand portion of Fig. 1, but showing the applying tool in a different position relative to the end of the anchor.

Fig. 4 is an end view of the anchor and applying tool illustrating their positions when the anchor has been driven to its applied position.

Fig. 5 is a side view of the anchor and applying tool illustrating the positions of said members shown in Fig. 4.

Fig. 6 is a diagrammatic view illustrating several positions assumed by the applying tool when it is driven transversely of the rail, and

Fig. 7 illustrates a modified embodiment of applying tool, the applying tool and the anchor being illustrated in this figure in their initial inclined positions.

In order to afford a clear understanding of the operation of my improved device for applying rail anchors to railroad rails, I have illustrated the present invention in connection with a one-piece spring yoke anchor of the type shown in United States Letters Patent No. 1,619,902, issued March 8, 1927. The one piece anchor of the type referred to may be briefly described as consisting of a spring yoke 10, formed at one end with a relatively long angularly disposed jaw 11 adapted to be hooked over a rail base flange at one side of the rail 12, and formed at the other end with a shorter jaw 13 adapted to be driven into gripping engagement with the base flange at the opposite side of the rail. The body of the yoke is formed with a normal torsional set so that the jaws 11 and 13, when the anchor is in its initial position on the rail, normally stand at an angle to each other so that it is necessary to twist the anchor to engage the jaw 13 over the edge of the rail base.

The anchor herein shown is applied as follows: The angularly disposed jaw 11 is hooked over the rail base, as shown in Fig. 1, and the short jaw 13 is then raised to a position adjacent the edge of the rail base. In this position of the anchor, the lower edge 14 of the jaw 13 is slightly below the upper edge of the rail base, as shown in Figs. 1 and 2. The yoke is then twisted in a direction to move the yoke from the inclined position shown in Fig. 2 to a position substantially perpendicular to the bottom surface of the

rail base (Fig. 4). As soon as the anchor has been twisted sufficiently to permit the edge 14 to clear the upper corner of the rail base, it is driven transversely of the rail 5 from the position shown in Fig. 1, to the position shown in Fig. 5. During this transverse movement of the anchor, the long jaw 11 slides downwardly on the inclined top surface of the rail base and the short jaw 10 10 13 and the upper edge 15 of the bar 10 are forced into frictional gripping engagement with the top and bottom surfaces, respectively, of the rail base 16.

In the drawings, I have shown two embodiments of my invention adapted for use in applying anchors of the above general type to the base flanges of railroad rails. The embodiment shown in Figs. 1 to 6, inclusive, consists of a member 17 formed with 20 a down-turned flange 18 spaced with relation to the body portion of the member so as to provide a hook shaped portion adapted to embrace the jaw end 13 of the anchor. The vertical edge 19 of the member 17 is formed 25 with a recess 20 adapted to receive one flange of the rail base, and the lower end of the said member is formed with a shoulder 21 adapted to so engage the anchor device as to support it in its initial position on the rail 30 (Figs. 1 and 2). The width of the recess 20 is somewhat greater than the recess below the jaw 13 of the anchor and also somewhat greater than the portion of the rail base flange received therein and is so disposed 35 with relation to the lower edge 22 of the downturned flange 18 that the said member 17, when in its initial engagement with the rail base (Fig. 1) may assume a position at 40 an oblique angle to the bottom surface of the rail base, as shown in Fig. 2. Preferably the lower edge 23 of the recess 20 and the said lower edge 22 of the flange 18 are tapered in opposite directions to provide cam surfaces 24 and 25 which, when the member 17 45 is in its angular position, will bear against the top and bottom corners respectively of the rail base. The said cam surfaces 24 and 25, in addition to being inclined transversely of the rail, are also tapered longitudinally 50 of the rail, so as to provide relatively wide bearing surfaces for engagement with the top and bottom surfaces of the rail base during the various positions assumed by the member 17 (Fig. 6) during the movement of 55 the said member transversely of the rail. The width of the member 17 is preferably such that, when the recessed edge is in engagement with the base flange of the rail, as shown in Fig. 1, the edge 26 of the member 60 will extend beyond the edge 27 of the anchor device, as shown in Fig. 1. In operation, the anchor jaw 11 is hooked over one base flange of the rail and the jaw 13 raised to the position shown in Fig. 1. The applying tool 17 65 is slipped over the jaw end 13 of the anchor

and moved transversely of the rail until the edges of the cam surfaces 24 and 25 engage the upper and lower corners of the base flange 16 of the rail. The member 17, when in its above initial position supports the jaw 70 end 13 of the anchor. By driving the member 17 transversely of the rail from its initial position, the said cam surfaces are forced over the longitudinal corners of the base flange and thereby rock the member 17 to 75 ward a position perpendicular to the bottom surface of the rail base. The movement of the member 17 from the position shown in Fig. 1 and the position A of Fig. 6, toward the position shown in Fig. 4 or the position 80 C of Fig. 6, subjects the anchor 10 to torsional stress and moves the lower edge 14 of the anchor jaw 13 into a position to clear the upper corner of the rail base. The last named positions of the anchor and applying 85 tool are assumed by said members when the tool has been driven to such position that the edge 26 of the tool aligns with the edge 27 of the anchor, as shown in Fig. 3. The driving force may now be applied simultaneously 90 to the edges 26 and 27 of the tool and the anchor, so that both members will be driven transversely of the rail. The lower edge 14 of the jaw 13 and the upper edge 15 of the body of the anchor move into engagement 95 with the top and bottom surfaces of the rail base before the applying tool reaches the limit of its full movement. This engagement of the anchor with the rail relieves the applying tool from the spring 100 pressure exerted by the twisted condition of the anchor and consequently removes the frictional engagement of the applying tool on the rail base. When the anchor reaches the position above referred to, that is to say, 105 before it reaches its fully applied position, the applying tool may be readily removed by hand and the anchor then driven home by striking the edge 27 thereof. However, if it is desirable, the applying tool need not be 110 removed until the anchor has been driven home.

In Fig. 7 I have shown another embodiment of my invention, in which a flat bar is provided along one edge with a recess 28 115 adapted to receive the short jaw end of the anchor. The recess is so formed as to provide a guiding lug 29 for the upper edge of the anchor device and to provide also a seat portion 30 for the lower edge of the anchor. The tool shown in this embodiment is provided with a relatively long handle portion 31 so that the anchor may be twisted with 120 minimum exertion. In this embodiment, the anchor device is twisted and held manually in its twisted position while the jaw end thereof is driven through the guiding recess 28 of the applying tool and into operative gripping engagement with the rail base.

While I have described my invention in 130

connection with two specific embodiments, it will be obvious that further modifications might be made without departure from the spirit of the invention. It will therefore be understood that I contemplate all such changes that come within the scope of the appended claims.

I claim:

1. A device for use in applying rail anchors, comprising a member formed with a recessed portion adapted to fit over one end of a rail anchor and provide a support for the lower edge portion thereof and provided with means whereby force applied to the device in one direction exerts a torsional stress on said anchor.

2. A device for use in applying rail anchors, comprising a member formed with a recessed portion adapted to fit over one end 20 of a rail anchor and provided with means engaging the rail base, whereby force applied to the device in one direction exerts a torsional stress on said anchor.

3. A device for use in applying rail anchors, comprising a member formed with a recessed portion adapted to fit over one end 25 of a rail anchor and provided with means engaging the rail base, whereby force applied to the device to move it transversely of the rail subjects the rail anchor to torsional stress.

4. A device for use in applying rail anchors, comprising a member formed with a recessed portion adapted to fit over one end 35 of a rail anchor and provided with a cam surface adapted to engage the rail base, whereby movement of the device transversely of the rail tilts the device in a direction to torsion the anchor.

40 5. A device for use in applying rail anchors, comprising a member formed with a recessed portion adapted to engage one end of a rail anchor and provided with means for engaging the adjacent flange of a rail base and adapted by movement longitudinally of said anchor and transversely of said rail to subject the rail anchor to torsional stress.

6. A device for use in applying rail anchors to railroad rails, comprising a member formed with means for engaging the lower portion and a side face of a rail anchor and provided with a portion adapted to bear against the rail base flange, whereby movement of the device transversely of the rail tilts the device and subjects the anchor to torsional stress.

7. A device for use in applying rail anchors to railroad rails, comprising a member formed with means for engaging the lower edge portion and a side face of a rail anchor and provided with a portion adapted to bear against the rail base flange, whereby initial movement of the device transversely of the rail raises a jaw portion of

the anchor with relation to the rail base and maintains said jaw in a raised position during further movement of the device.

8. A device for use in applying rail anchors to railroad rails comprising a member formed with means for engaging the lower edge portion and a side face of a rail anchor and provided with a cam surface adapted to bear against the top surface of the rail base flange, whereby movement of the device transversely of the rail tilts the device and subjects the anchor to torsional stress.

9. A device for use in applying rail anchors to railroad rails, comprising a member formed with means for engaging the lower edge portion of a rail anchor, means embracing the upper edge of the rail anchor, and means adapted to bear against a portion of the rail base, whereby movement of the device transversely of the rail tilts the device and subjects the anchor to torsional stress.

10. A device for use in applying anchors to railroad rails, comprising a member formed with means for engaging the lower edge portion of a rail anchor, means embracing the upper edge of the rail base and adapted to bear against the inclined upper surface of the rail base, whereby movement of the device transversely of the rail tilts the device and subjects the rail anchor to torsional stress.

11. A device for use in applying rail anchors to railroad rails, comprising a member formed with means for engaging the rail anchor near the lower edge thereof, means embracing the upper edge of the rail anchor and formed with a tapered surface adapted to bear against the inclined upper surface of the rail base, whereby transverse movement of the device with respect to the rail subjects the anchor to torsional stress.

12. A device for use in applying rail anchors to railroad rails, comprising a member formed with means for engaging the rail anchor near the lower edge thereof and having a recess adapted to receive the adjacent edge of the rail, one edge of said recess being formed with a cam surface adapted to bear against the rail base, whereby movement of the device transversely of the rail tilts the device in a direction to exert a twisting stress on said rail anchor.

13. A device for use in applying rail anchors to railroad rails, comprising a member formed with means for engaging the lower edge of a rail base, and formed with a down-turned flange one edge of which is formed with a cam surface adapted to bear against the top surface of the rail base, whereby movement of the device transversely of the rail tilts the device in a direction to subject the rail anchor to torsional stress.

14. A device for use in applying rail an-

chors to railroad rails, comprising a member formed with a recess one edge of which is tapered both longitudinally and transversely of the rail and adapted to bear against the lower corner thereof, a down-turned flange for embracing the upper edge of the anchor and provided with a surface

tapered both longitudinally and transversely of the rail and adapted to bear against the top surface of the rail base, whereby movement of the device transversely of the rail tilts the device in a direction to subject the anchor to torsional stress. ¹⁰
